UNITED STATES PATENT OFFICE.

SWAN SWANSON, OF SEATTLE, WASHINGTON.

DESIGN FOR A BOTTLE-CAP.

53,092.

Specification for Design.

Patented Mar. 11, 1919.

Application filed April 25, 1917. Serial No. 164,572. Term of patent 7 years.

To all whom it may concern:

Be it known that I, SWAN SWANSON, a citizen of the United States, and a resident of Seattle, in the county of King and State of Washington, have invented a new, original, and ornamental Design for a Bottle-Cap, of which the following is a specification, reference being had to accompanying drawing, forming a part thereof.

This invention relates to a design for a bottle cap.

Figure 1 is a perspective view of my ornamental bottle cap.

Fig. 2 is a side elevation of same.

Fig. 3 is an elevation of the bottle cap.

Claim—

The ornamental design for a bottle cap, as shown.

S. SWANSON.
